AERATED GRADUAL REDUCTION FLOUR MILLING SYSTEM

Clark A. McElevey, Grand Marais, Minn.

Application May 22, 1952, Serial No. 289,260

5 Claims. (Cl. 241—42)

1

My invention relates to improvements in a gradual reduction flour milling system for aerating the various machinery utilized in the milling of flour, and has for its purpose to both increase the efficiency of the aeration of the stock streams as they pass through the flour mill, and to effect a substantial saving of the higher grades of stock picked up by the air streams which, under present conditions, end up as feed or low grade stocks.

This application is a continuation-in-part of my pending application Serial No. 673,123, filed May 29, 1946, and entitled "Method of Aerating Flour Milling Equipment."

Flour milling as it is understood today, is based on an arrangement of equipment to arrive at the end product. The wheat berries are introduced into the head end of the mill and after a number of reductions and classifications, the several products and by-products merge as a result. It is not possible to totally break the wheat berry down in one operation because of the differences in the physical characteristics of the wheat berry at different levels. The exterior shell of the wheat berry is not desirable for good flour. The next immediately underlying portion of the berry (perhaps 40 to 50 per cent of it towards the heart), makes a very high grade flour; whereas the portion of the berry around and including the heart makes a lower grade flour. For this reason, equipment within the flour mill usually is arranged to provide a plurality of stock streams, in each of which the berries are reduced to a desired predetermined extent. Usually there are five or six reductions; that is, five or six separate grade streams through which the wheat berries pass in the milling process. For illustration, the average mill has a first, second, third, fourth and fifth break; middling rolls; and tailed rolls. Each separate stock stream may include varying types of equipments such as rolls or breaks, sifters, purifiers, etc. The products tailed over from one stock stream are conveyed by various methods to the next grade stock stream in line.

In the milling operations through the various machines in the several grade stock streams, it is necessary to have certain quantities of air for evaporative cooling and aspiration. The standard practice of providing air for this purpose is, and for many years, has been to base the air requirements upon the total group of flour milling equipment involved, irrespective of and without regard to the number of stock grade streams being aerated by a given air stream. For example, in a flour mill having all of the breaks

2

on a given floor, it would be common practice to aerate all of the breaks by a common air stream with a result that the air stream would so commingle stock from the first, second, third, fourth and fifth breaks, and so on, that it could not thereafter be economically separated. Consequently, all such stock is run into the feed or low grade stock streams where it brings a price far below the prices which the various constituents of the air stream would bring if they could be separated.

In order to avoid this loss, flour mill designers lean over backward in an effort to hold to a minimum the volume of air used in aerating milling equipment—with a result that frequently less air is provided than is required to do the job efficiently.

I have, by considerable experimentation, learned that by aerating each of the several stock streams in a flour mill, by an independent air stream, and returning i. e., conveying the stock picked up by each of said air streams, to the same stock stream or a higher grade stock stream from which it was removed that not only can a substantial saving of high grade flour be effected, but also that an increased volume of air can be used where and if desired.

The above and still further highly important objects and advantages of my novel method will become apparent from the following detailed specification, appended claims and attached drawing.

Referring to the drawing, the single view is a diagram illustrating the flow of stock through various components of a conventional flour mill and the manner in which my novel method is employed.

The preliminary treatment of the grain prior to the breaking of the wheat berries and including the cleaning, scouring, tempering etc., of the grain berry in itself does not comprise the instant invention. Hence, for the sake of brevity, equipment utilized in the above mentioned operations is not shown nor is it deemed necessary for further description, said operations being conventional and achieved by conventional methods and means.

The mill illustrated includes a breaking system comprising a plurality of breaking rolls 1 to 5, inclusive, each breaking roll feeding to a respective bolt or sifter unit, said units being indicated at 6 to 10, inclusive. A purifier system includes a plurality, in this instance four, of purifiers 11, 12, 13 and 14. The purifiers receive endosperm particles from the breaking

system and separate the same. From thence, the screenings thereof are conveyed to a middlings reduction system comprising a plurality of reduction rolls 15 to 24, inclusive. Each set of reduction rolls of the middlings reduction system is associated with and feeds stock to a respective bolt or sifter 25 to 34, respectively. The tailings from the several purifiers 11 to 14, inclusive and from several of the middlings reduction units are conveyed to a first of a series of tailings reduction rolls 35, 36 and 37 of a tailings reduction system comprising said tailings reduction rolls and respective associated bolts or sifters 38, 39 and 40.

As the wheat enters the first break rolls 1 from the head end of the mill, the hull of the wheat berry is broken to expose the endosperm. During the breaking operation, the wheat germ is released and separated from the stock stream by suitable means, not shown. The stock stream is subject to the sifting or separating equipment in the sifter 6, a portion of the tailings thereof being conveyed to the purifier 11, as indicated by the dotted flow line 41. Other tailings are conveyed to the second break rolls 2, as indicated by the flow line 42. Still other tailings are delivered to the second purifier 12, as indicated by the dotted flow line 43. The screenings from the sifter 6 emerge at 44 in the nature of grade B flour in relatively small amounts. The material received by the break rolls 2 is fed to the sifter 7 from whence tailings are delivered to the next break rolls 3, as indicated by a flow line 45, where they are further reduced and subject to the action of the sifter 8. Certain of the tailings from the sifter 8 are delivered to the break rolls 4, as indicated by the flow line 46, where the material is further reduced and subjected to the action of the sifter 9 which delivers tailings to the break rolls 5, as indicated by a flow line 47. From the final break rolls 5, material is fed to the sifter 10 associated therewith which tails off branney material used as feed, as indicated by a flow line 48. A certain portion of the tailings from the sifter 7 are carried to the purifier 11, as indicated by a flow line 49 and a portion of flow line 41. Other tailings from the bolt or sifter 7 are carried to the second purifier 12, as indicated by a flow line 50 and part of the flow line 43. In like manner, a certain portion or grade of tailings from the bolt 8 are delivered to the purifier 12, as indicated by a flow line 51 and a portion of the flow line 43, while another portion or grade of tailings from the bolt or sifter 9 is delivered to a third purifier 13, as indicated by a flow line 52. The screenings from the sifters 7 and 8, like those of the sifter 6, comprise a B grade flour and are discharged from their respective sifters, as indicated at 53 and 54. Certain of the tailings from the sifter 9 are delivered to the purifier 14 as indicated by a flow line 55. The screenings from the sifters 9 and 10 comprise a lower or C grade flour and are discharged as indicated at 56 and 57, respectively. From the above, it will be seen that stock flows in a stream from the sifter 6 through the break rolls 2, 3, 4 and 5 and the sifters associated therewith, the products of which comprise grades B and C flour, the branney feed and the like being tailed off as indicated at 48.

From the purifier 11, the endosperm particles are delivered to the reduction rolls 15, as indicated by a flow line 58, where they are broken up and subjected to the action of the sifter 25, the screenings thereof comprising grade A or patent

flour and discharged as indicated at 59. Some of the more branney particles are tailed off from the sifter 25 and delivered to the reduction rolls 35 of the tailings reduction system as indicated by a flow line 60. Other tailings from the sifter 25 are delivered to the reduction rolls 16 as indicated by a flow line 61. Material passing through the reduction rolls 16 is subject to the action of the sifter 26, some of the tailings therefrom being delivered to the tailings reduction rolls 35, as indicated by a flow line 62 and a portion of the flow line 60. These tailings also contain branney particles. Other portions of the stock from the sifter 26 are tailed off to the reduction rolls 17, as indicated by a flow line 63 where they are further reduced and subjected to operation of the sifter 27. A portion of the tailings from the sifter 27 are delivered to the tailings reduction rolls 35, as indicated by a flow line 64 and part of the flow line 60, whereas the tailings from the sifter 27 are delivered to the middlings reduction rolls 18, as indicated by a flow line 65. The stock stream passing through the reduction rolls 18 is subject to the action of the sifter 28, some of the material being tailed off therefrom and delivered to the first tailings reduction rolls 35, as indicated by a flow line 66 and a portion of the lines 64 and 60. The balance of the tailings from the sifter 28 is delivered to the reduction rolls 19, as indicated by a flow line 67 from whence the tailed over and further reduced stock is subjected to the operation of the sifter 29. Like the screenings from the sifter 25, the screenings from the sifters 26 to 29 inclusive, comprise grade A or patent flour and are discharged from the several sifters as indicated at 68, 69, 70 and 71, respectively. It should be noted that the stock stream resulting in the grade A flour is fed to the middlings reduction rolls 15 to 18 inclusive, not only from the purifier 11 but also from the purifiers 12 to 14, inclusive. A portion of the material discharged by the purifier 12 is delivered to the first middlings reduction rolls 15, as indicated by a flow line 72 and part of the flow line 58. Another portion of the material discharged by the purifier 12 is delivered to the reduction rolls 16, as indicated by a flow line 73. The reduction rolls 16 also receive material from the purifier 13, as indicated by the portion of the flow line 73 and a flow line 74. Other portions of material discharged by the purifier 13 are delivered directly to the reduction rolls 17, as indicated by a flow line 75, said rolls 17 also receiving a portion of the discharge from the purifier 14, as indicated by a flow line 76 and part of the flow line 75. The balance of the material discharged from the purifier 14 is delivered directly to the reduction rolls 18, as indicated by flow line 77. From the above it will be seen that the material delivered to the middlings reduction rolls 15 to 18 inclusive from their associated purifiers and to each of the reduction rolls 16 to 19, inclusive, together with their respective sifters, comprises a stock stream resulting in grade A flour.

The purifiers 11 to 14, inclusive, discharge tailings of a lower grade than that required for grade A flour and such material is conveyed or delivered to the tailings reduction system. As shown, some of these tailings are delivered from the purifier 11 to the tailings reduction rolls 35 as indicated by a flow line 78 and a part of the flow line 60. The above mentioned material discharged from the purifiers 12, 13 and 14 is conveyed as indicated by respective flow lines 79, 80

and 81 which merge with the flow indicated by the line 78.

Certain of the tailings discharged by the sifter 29 are delivered to the middlings reduction rolls 20, as indicated by a flow line 82 from whence they are subjected to the action of the sifter 30, the screenings therefrom discharged as grade B flour, as indicated at 83. The sifter 30 discharges tailings which are delivered to the next reducing rolls 21, as indicated by the flow line 84, from whence the material is received by the sifter 31. The screenings discharged by the sifter 31 emerge as grade B flour at 85. Tailings discharged from the sifter 31 are delivered to the next middlings reduction rolls 22, as indicated by a flow line 86, and from thence to the sifter 32 associated therewith, the resultant screenings of which emerge as grade B flour, as indicated at 87. The middlings reduction rolls 20 to 22, inclusive, and their associated sifters 30 to 32, inclusive respectively, operate on a stock stream which, although being a combination of the stock stream which provides grade A or patent flour, may be assumed to be and is treated as a separate stock grade stream in that it produces a different grade flour, namely grade B flour. The last sifter in this series, namely the sifter 32, discharges tailings which are delivered to the middlings reduction rolls 23 as indicated by a flow line 88, from whence the material is received by its associated sifter 33, the screenings of which emerge at 89 as grade C flour. The tailings discharged from the sifter 33 are conveyed to the final middlings reduction rolls 24 as indicated by a flow line 90, from whence they are received from the final sifter 34 associated therewith. The product of the sifter 34 emerges as grade C flour at 91.

The tailings received by the first tailings reduction rolls 35 from the several purifiers and the middlings reduction sifters 25 to 28, inclusive, are further reduced and subject to the action of the sifter 38, the screenings of which emerge as grade B flour, as indicated at 92. The tailings from the sifter 38 are delivered to the second tailings reduction rolls 36, as indicated by the flow line 93. It should here be noted that a certain percentage of the tailings from the final sifter in the series which produces grade A flour, namely, the sifter 29, is delivered to the second tailings reduction rolls 36, as indicated by a flow line 94. The sifter 39 receives material passing through the reduction rolls 36 and produces grade C flour discharged therefrom as indicated at 95 and tailings which are delivered to the final tailings reduction rolls 37, as indicated by a flow line 96. The final sifter 40 in the tailings reduction system also produces grade C flour, as indicated at 97.

In the drawing, the various flow lines indicating the flow of stock through the mill in the producing of the various grades of flour, feed and the like, is indicated by relatively light dotted or broken lines. It should be borne in mind that the above described arrangement is but one of a number of arrangements of flour milling equipment. The means for conveying the stock through the mill, such as conveyor ducts, belts, elevators and the like are indicated broadly by the flow lines above described, such equipment being conventional.

My improved method of aerating flour milling equipment utilizes a plurality of centrifugal separating devices and associated motor-driven fans or blowers connected by suitable conduits or the like to various component elements of the milling

equipment in such a manner that particles of stock held in air suspension in said components in each of a plurality of stock streams will be removed separately by separate air streams generated by the fans and settled-out in the centrifugal separators, the settled-out stock or flour constituents being delivered to the same stock grade stream from whence it was taken, or a higher grade stock stream from whence it was removed. In the diagram illustrated, this arrangement is carried out through the entire system illustrated, with a single exception, that exception being the aeration of the first break rolls 1 and the sifter 6 associated therewith. In this case, the settled-out flour is not returned to a stock stream, but is delivered by conventional means, not shown, to a suitable destination for packaging or other treatment.

The stock stream flowing through the middlings reduction rolls 15 to 19, inclusive, and their associated sifters or separators 25 to 29, inclusive, respectively, is aerated by a fan 98 which may be assumed to be driven by a motor, not shown, and which delivers the air to a centrifugal separator 99 of conventional design. The flour-laden air is drawn by the fan 98 from the various machines in the stock stream which provides grade A flour through a duct system including a main conduit 100 and a plurality of branch conduits 101 connecting the main conduit 100 with the several middlings reduction rolls 15 to 19, inclusive, the sifters 25 to 29, inclusive, and other equipment associated therewith but not shown. As shown, the conduits 100 and 101 are indicated by relatively heavy solid lines in the drawing. The flour which is settled-out in the centrifugal separator 99 is delivered by suitable means to the final reduction rolls 19 of the group of equipment which produces grade A or patent flour as indicated by the heavy broken or dotted flow line 102 and a portion of the flow line 67. Similarly, the stock grade stream of the middlings reduction system which produces grade B flour, namely, the reduction rolls 20 to 22, inclusive, the associated separators 30 to 32, inclusive, and other related equipment, not shown, is aerated by a separate air stream generated by a motor-driven fan 103 which draws flour-laden air from said equipment through a main conduit 104 and branch conduits 105. The fan 103 delivers the flour-laden air to a centrifugal separator 106 from whence the settled-out flour is returned to the final reduction rolls 22, as indicated by the heavy dotted or broken flow line 107.

The stock stream passing through the first break rolls 1 and the sifter or separator 6 associated therewith, is aerated by an air stream generated by a motor-driven fan 108, as indicated by a heavy solid flow line 109. The fan 108 feeds the flour-laden air to a centrifugal separator 110, the flour settled-out therefrom being a grade D or feed flour. As above stated, this flour is conveyed by suitable means to a point for further treatment.

The remaining sets of break rolls 2 to 5, inclusive, and their associated sifters 7 to 10, inclusive, are aerated by a common air stream generated by a motor-driven fan 111 connected to said break rolls and sifters by suitable conduit means indicated by a relatively heavy solid flow line 112 and branch conduits illustrated by flow lines 113. Bearing in mind that the sifters 7 and 8 produce grade B flour, whereas the sifters 9 and 10 produce grade C flour, a loss of savings would occur if the flour gathered from these ma-

chines were discharged to a stock stream of the lower grade such as produces grade C flour. In this instance, however, the flour gathered by the fan 111 is settled out in a centrifugal separator 114 and delivered to equipment which results in grade B flour; namely, the first tailings reduction rolls 35 and the sifter 38. As shown by the relatively heavy dotted flow line 115 and portions of the flow lines 78 and 80, the settled-out flour is delivered to a point where it will be separated to provide grade B and grade C flour. Such combining of the stock streams is permitted where the quantity of flour is not too great and where separation thereof is not too difficult. Such an arrangement is also sometimes dictated by the lay-out of the mill and the possible expense involved in setting up the aerating equipment. In the arrangement illustrated, it will be seen that the fan 111 and separator 114 aerate the rolls 23 and 24 and sifters 32 and 34 of the middlings reduction units which produce grade C flour as well as the entire tailings reduction system as illustrated by a portion of the flow line 112, a flow line 116 and branch lines 117.

The particles of material or flour in air suspension in the purifiers 11 to 14, inclusive, are drawn by a fan 118 through a conduit illustrated by a flow line 119 and branch conduits 120, and fed to a centrifugal separator 121 from whence the settled-out flour is delivered to the tailings reduction rolls 35, as indicated by a heavy dotted flow line 122; a portion of the flow lines 115, 78 and 80.

With the above arrangement, I am able to employ a greater volume of air at pressures sufficient to thoroughly aerate the various machines and equipment in a flour mill system and I have found that savings up to two per cent (2%) of high grade flour removed from the stock streams can be effected, such high grade flour heretofore having gone into the lower grade stock or feed streams because of the difficulty of separation.

What I claim is:

1. In a gradual reduction flour milling system comprising a breaking system having a series of sets of break rolls and a corresponding series of sifters producing grade A flour, middlings and tailings; the improvement comprising in combination with said break rolls and sifters, of a middlings reduction system having a first grade A flour producing section and a second grade B flour producing section, each of said sections including a series of sets of break rolls and corresponding sifters, a ventilating means for said gradual reduction system comprising at least two suction fans and cooperating separators, one fan and its separator having an air inlet connection with the rolls and sifters of said first section and the other fan and separator having an air inlet connection with the rolls and sifters of said second section, and each of said separators having means for returning the collected product to a set of rolls of its reduction section, whereby an increase in the production of grade A flour from said breaking system is effected.

2. In a flour milling system as defined in claim 1, in which the middlings reduction system also includes a third grade C flour producing section having a series of sets of break rolls and corresponding sifters, a tailings reduction system having a series of sets of break rolls and corresponding sifters, and said ventilating means includes another suction fan and corresponding separator, said fan having an air inlet connection with the rolls and sifters of said third section and also the rolls and sifters of said tailings reduction section, and said separator having means for conveying the product collected thereby to one of said sets of rolls of said tailings reduction system.
3. In a flour milling system as defined in claim 1, and having a tailings reduction system including a series of sets of break rolls and corresponding sifters, and wherein said ventilating means includes another suction fan and cooperating separator, means connecting the air inlet of said fan with the sets of break rolls and sifters of said breaking system, and said separator having means for conveying the product collected thereby to one of said sets of break rolls of said tailings reduction system.
4. In a flour milling system as defined in claim 3, wherein the inlet of said fan is connected to the rolls and sifters of both the breaking system and the tailings reduction system.
5. In a flour milling system as defined in claim 4, wherein a series of purifiers is interposed between the series of sifters of the breaking system and the series of sets of rolls of the first section of the middlings reduction system and delivering grade A flour to the latter, and said ventilating means includes a further suction fan and cooperating separator; said fan having means connecting the air inlet thereof to said series of purifiers, and said separator having means for conveying the products collected thereby to one of said sets of rolls of said tailing reduction system.
